PISTON EXPANDER

Charles F. Johnston, Oakland, Calif.

Application October 2, 1934, Serial No. 746,490

18 Claims. (Cl. 309—12)

The invention relates to means arranged for use in connection with a piston for holding the skirt of the piston in expanded relation whereby the latter may compensate for the wearing 5 in the cylinder walls and resulting in what is generally known as "piston slap".

An object of the invention is to provide a means of the character described which will operate directly on the longitudinal slot provided 10 in the piston skirt for expanding the circumference of the skirt and which will afford a degree of resilient flexibility for enabling the piston to vary in diameter during the course of its movement to snugly conform to minor variations 15 in the cylinder bore.

Another object of the invention is to provide a means of the character described which will be comprised of a single one piece member, so designed as to afford a maximum resilience and 20 strength for the amount of material used, whereby the same will be of minimum size and weight and of simple and inexpensive manufacture.

A further object of the invention is to provide a means of the character described which will afford the desired expansion of the piston skirt 25 for the full length thereof without requiring any departure from the design of the conventional type of piston.

Still a further object of the invention is to 30 provide a piston skirt expanding means which may be absolutely locked in operative position in the piston without requiring the provision of any attaching parts to the piston or the use of any attachments between the piston and the expander.

The invention possesses other objects and features of advantage, some of which, with the foregoing, will be set forth in the following description of the preferred form of the invention which is illustrated in the drawing accompanying and forming part of the specification. It is to be understood, however, that variations 40 in the showing made by the said drawing and description may be adopted within the scope of the invention as set forth in the claims.

Referring to said drawing:

Figure 1 is a side elevation of a piston with the expander of my invention applied thereon.

Figure 2 is a vertical sectional view showing 50 the inside of the piston of Figure 1 and the attachment of my expander thereto.

Figure 3 is an enlarged outside view similar to Figure 1.

Figure 4 is a sectional view taken substantially 55 on the plane of the line 4—4 of Figure 1.

Figure 5 is a perspective view of the expander.

Figure 6 is an enlarged view taken inside of the piston and showing a modified form of my invention.

Figure 7 is a perspective view of the modified 5 form of expander shown in Figure 6.

As illustrated in Figures 1 to 5 of the drawing, the expander member 2 of my invention is arranged for positioning on the inside of a piston 3 such as used in an internal combustion engine. 10 More specifically the member 2 is arranged for positioning within the portion 4 of the piston, usually termed the skirt and which includes the sides of the piston extending to the open end 6.

In the type of piston with which the means of my invention is arranged for use, the skirt portion 4 is provided with a longitudinal slit 7 which extends from a point adjacent the ring retaining portion 5 of the piston to the end 6. 20 At the inner end of the slit, that is adjacent the portion 5, the slit is communicated with a cross or circumferentially extending slit 8 which permits the skirt portion adjacent the slit 7 of a limited outward expansion.

In accordance with the present invention, I provide a means which is arranged to engage directly in the slit 7 for spreading the same and for effecting an expansion of the skirt portion of the piston. As here shown, the means comprises 30 a flat spring member 11 formed with opposed leg portions 12 which are interconnected at an end by a loop portion 13. In the embodiment shown in Figures 1 to 5, the free ends 15 of leg portions are spaced somewhat so as to resiliently resist 35 being brought together and are formed with outstanding lugs 14 which are arranged for engaging in the slot 7 so that when sprung thereinto, the member 11 will be strained to set up an expanding action on the piston skirt. In order that 40 the member may be positively locked against loosening from an engaged position in the piston, the latter is preferably drilled at the slit 7, preparatory to insertion of the expander, so as to define the skirt at opposite sides of the slit opposing seat or socket portions 16 for engagement 45 with the lugs 14. Also the lugs are preferably flared outwardly from the plane of the leg sides and formed with sharply defined outer corners which cause the lugs, under the urge of the 50 strained member, to bite or cut into, and lock themselves in, the socket portions 16. If desired and as perhaps best seen from Figures 5 and 6 the sides of the leg portions may be convergently tapered towards the free ends thereof so as to 55

- reduce the overall transverse extension of the lugs 14 with respect to the transverse dimensions of the opposite end of the member. When arranged in this manner, the expander may be stamped or otherwise formed from a rectangular blank of material with a minimum of material wasted in the forming of the lugs and at the same time utilizing the wider folded end of the blank for strengthening the expander.
- 10 As a particularly important feature of the invention, the side or leg portions of the expander are bowed over their length so as to converge from the interconnecting loop portion 13 into closely opposed position at portions 17 intermediate their ends and then diverge into well spaced position at the free ends 15 thereof. Thus on drawing the free ends together, the portion 17 will be moved into contact to provide on further approachment of the ends for the setting up over the length of the leg portions, a double cantilever spring action which is produced, as will be understood, by reason of the attachment of the ends at the loop portion 13 and the fulcruming of the legs on the intermediate portions 17. By reason of this double cantilever action a very considerably greater force may be developed for the short movement required than could otherwise be obtained and as a result a considerably smaller and lighter member may be used.
- 20 A modified form of the invention has been shown in Figures 6 and 7 wherein the leg portions 12' of the expander are bowed slightly to space the intermediate portions thereof but to engage the free ends 15'. The lugs 14' are provided on intermediate portions of the legs whereby their movement together is resiliently resisted by a flexing of the legs between their ends. In this manner not only are the legs stiffened by their engagement at the interconnecting loop portion 13' but also by their engagement at their free ends 15'. Thus the stress set up in the expander by reason of a drawing together of the lugs 14' will be distributed over the full length thereof with the result that, as in the case of the first described embodiment, a maximum expansion force may be obtained for a minimum size and lightness of material.
- I claim:
1. In an expander for a piston having the skirt portion thereof provided with a longitudinal slit recesses in the opposite side faces of said slit opening into said slit, a generally U shaped flat spring member provided with opposed longitudinal leg portions adapted for mounting at the inner side of said piston in substantially parallel relation to said slit and having transverse projections arranged to be sprung into said recesses for circumferentially expanding said piston.
  2. In an expander for a piston having the skirt portion thereof provided with a longitudinal slit, a flat spring folded to define a pair of opposed leg portions, projections provided on said leg portions adjacent the free ends thereof and arranged to be sprung into said slit for spreading said slit, said leg portions being bowed over their length so as to contact and provide a fulcruming support for each other intermediate their lengths.
  3. In combination with a piston having the skirt portion thereof formed with a longitudinal slit and provided with opposed recesses opening to said slit, an expander having longitudinal sides arranged for mounting opposite said slit at the inner periphery of said skirt and each provided with an offset portion arranged for engagement in said recesses for spreading said slit.

4. In combination with a piston having the skirt portion thereof formed with a longitudinal slit and provided with opposed recesses opening to said slit, a spring member having longitudinal sides arranged to engage the inner periphery of said skirt at opposite sides of said slit and provided with portions thereof arranged for engagement in said recesses for spreading said slit.

5. In an expander for a piston having the skirt portion thereof formed with a longitudinal slit, a flat spring member folded to provide a pair of opposed side portions, said side portions being bowed to space the intermediate portions thereof and arranged on drawing together to contact adjacent the free ends thereof, and projections carried by said intermediate portions and arranged to be pressed towards each other and sprung into said slit for expanding the piston.

6. In an expander for a piston having the skirt portion thereof formed with a longitudinal slit and provided with opposed curved recesses in the opposed skirt sides defining said slit, a spring having spaced projections arranged to be sprung into said recesses for spreading said slit, said projections being formed with sharply defined corners arranged to pierce into the curved walls of said recesses.

7. In an expander for a piston having the skirt portion thereof formed with a longitudinal slit and provided with opposed curved recesses in the opposed skirt sides defining said slit, a spring of elongated form having spaced projections arranged to be sprung into said recesses for spreading said slit, said projections being flared longitudinally of said spring and formed with sharply defined corners arranged to pierce into the curved walls of said recesses to resist withdrawal of said portions therefrom.

8. An expander for a piston having a longitudinal slit in the skirt portion thereof comprising, a flat spring member formed with spaced longitudinal sides interconnected at an end, and a transverse projection on each of said sides adjacent the other end thereof adapted upon positioning of said sides longitudinally within said piston to engage in said slit for spreading same, each of said sides being progressively narrowed in width from said first to said second end and being of a width at said projections substantially equal to the width of said opposite end.

9. In an expander for a piston having the skirt portion thereof provided with a longitudinal slit to permit expansion thereof, a spring member comprising, a pair of opposed sides supported one on the other at one point and connected at another and having spaced portions arranged to be sprung into said slit to engage and spread the opposed faces of said slit.

10. A piston having the skirt portion thereof formed with a longitudinal slit and provided with curved concave recesses at opposite sides of said slit in combination with, a spring member comprising, spaced compressible portions adapted to be sprung into said recesses for expanding said skirt and having sharply defined corners adapted to pierce the curved walls of said recesses to prevent relative turning.

11. In combination: a piston comprising a head portion and opposed thrust faces, one of said thrust faces having a longitudinal slot therein forming opposed edge faces, each of said edge faces having at least one notch therein extending transversely of said longitudinal slot; and a sheet metal expander comprising a resilient body having portions thereof in contact with the

inner surface of said slotted thrust face, said body also having a plurality of retaining lugs extending laterally therefrom, one of said retaining lugs being seated in each of said notches.

5. 12. A piston having a longitudinal slit in the skirt thereof in combination with an expander comprising, a body of resilient sheet metal folded to provide opposite members with free end portions adapted to be sprung towards each other 10 and inserted in said slit to provide on release and expansion of said portions for the expansion of said slit and piston, said body being formed to provide a support for said members adjacent said portions to increase the resilient resistance to the 15 springing of said edge portions together and to increase the resilient expansion of said portions against the sides of said slit.

13. A piston having a longitudinal slit in the skirt thereof in combination with an expander 20 comprising, a body having spaced opposed slit-face engaging portions adapted for contraction towards each other for insertion into said slit and connected remotely from each other to resiliently resist said contraction, said body also 25 being provided with bearing portions intermediate said connection and said first portions and being interengaged throughout substantially the full range of operative positions of said first portions to coact with said connection to increase the 30 resilient resistance to contraction of said first portions.

14. A piston having a longitudinal slit in the skirt thereof in combination with an expander comprising, a body having spaced opposed slit- 35 face engaging portions adapted for contraction towards each other for insertion into said slit and connected remotely from each other to resiliently resist said contraction, said body also provided with bearing portions adjacent said first portions and operating to resiliently hold apart said 40 first portions and coacting with said connection to increase the resilient resistance to contraction of said first portions.

15. In an expander for a piston having a longitudinal slit in the skirt thereof and a recess in 45

at least one of the opposed faces of said slit extending entirely through the wall of said skirt, a spring member adapted for mounting at the inner side of said skirt and having transversely projecting portions adapted for springing together 5 to a size permitting insertion thereof into said slit at said recess in a radial direction relative to said piston.

16. In combination, a piston comprising a head portion and opposed thrust faces, one of said thrust faces having a longitudinal slot therein forming opposed edge faces, each of said edge faces being formed with a recess extending entirely through the wall thereof, and opening to said slot, and an expander comprising a resilient 15 body adapted for positioning at the inner side of said slotted thrust face and having slot face engaging portions adapted for insertion into said recesses and being contractable towards each other to a circumferential width no greater than 20 the circumferential spacing of said recesses to enable insertion of said portions into said recesses in a radial direction relative to said piston.

17. In an expander for a piston having the skirt portion thereof formed with a longitudinal 25 slit, an elongated member adapted for mounting in the interior of said skirt adjacent said slit with its length in substantially parallel relation thereto, said member being curved lengthwise and provided with a plurality of laterally extending lugs 30 adapted for springing into said slit for spreading said skirt.

18. A piston having a skirt portion formed with a longitudinal slit and provided with a plurality of recesses in the opposed edge faces of said slit, 35 and an elongated member adapted for mounting in the interior of said skirt with its length in substantially parallel relation to said slit and for engagement with the wall of said skirt at said slit, said member being curved lengthwise and 40 provided with a plurality of retaining lugs at the opposite ends of said member engageable in said recesses.

CHARLES F. JOHNSTON. 45
